CENTRIFUGAL PUMP

William L. King, Eugene, Oreg., assignor to
L. W. James, Eugene, Oreg.

Filed Jan. 9, 1967, Ser. No. 5,354

Term of patent 14 years

(Cl. D65—1)

FIG. 1

FIG. 2

FIG. 3

FIG. 1 is a side elevational view of one side of a centrifugal pump in accordance with my new design;

FIG. 2 is a right end view, as viewed in the drawing; and

FIG. 3 is a left end view taken along the line 3—3 of FIG. 1.

The side opposite that shown in FIG. 1 is a mirror image of FIG. 1.

The elements shown in broken lines are included for illustrative purposes only.

I claim:

The ornamental design for a centrifugal pump, as shown and described.
